UNITED STATES PATENT OFFICE.

FREDERICK W. MOLDENHAUER, OF OCONOMOWOC, WISCONSIN.

STANCHION.

1,085,284.

Specification of Letters Patent.

Patented Jan. 27, 1914.

Application filed August 19, 1912. Serial No. 715,739.

To all whom it may concern:

Be it known that I, FREDERICK W. MOLDENHAUER, a citizen of the United States, and resident of Oconomowoc, in the county 5 of Waukesha and State of Wisconsin, have invented certain new and useful Improvements in Stanchions; and I do hereby declare that the following is a full, clear, and exact description thereof.

10 The object of my invention is to provide a simple, economical and effective animal stanchion especially designed for use in stabling cows, the construction and arrangement being such that a series of such stanchions can be simultaneously controlled, or 15 one or more separate stanchions may be separately controlled by manipulation of individual actuating rods that are adapted to be coupled to or uncoupled from a master controlling rod.

Other objects of my invention are to provide a two-arm lever for each stanchion that is in link connection with the bows thereof in such manner that the points of the lever 25 to which the links are attached travel to or beyond the center of said lever when the bows are closed to thus lock said bows positively without the aid of spring snaps or dogs usually employed for the purpose; to 30 provide means whereby the stanchion bows can swivel about a common axis when the said bows are closed; to provide individual manipulating rods for each stanchion lever that are adapted to be either coupled to the 35 master rod or detached therefrom and locked in connection with the usual overhead stanchion supporting rail; to provide a sectional stanchion rail and means for adjusting each section whereby the stanchion that is supported by said rail may be moved forward 40 or backward to accommodate different size cattle, and to provide means in connection with the ends of the stanchion bows whereby the same are supported in suspension 45 within a slot with which the sectional rail is provided.

With the above and other minor objects in view the invention consists in what is herein shown and described with reference 50 to the accompanying illustrations and subsequently claimed.

In the drawings Figure 1 represents a plan view of a stanchion mechanism embodying the features of my invention, the 55 stanchion bows being shown in their open position; Fig. 2, a sectional plan view of

the same with the parts shown in their open position, the section being indicated by line 2—2 of Fig. 3; Fig. 3, represents a side elevation of the stanchion and supporting frame therefor, parts being broken away and other parts in section to more clearly illustrate certain structural features with the stanchion bows shown in their closed position; and Fig. 4, a detailed plan sectional view across the stanchion bow ends illustrating the means for suspending the stanchion members, the section being indicated by line 4—4 of Fig. 3.

Referring by characters to the drawings, 70 1 represents vertical supporting posts having brackets 2 extending from their upper ends, the brackets being provided with seats for the reception of the ends of an overhead stanchion rail section 3, which rail is built 75 up from parallel members spaced apart and connected at their ends by filler blocks 3', whereby a slot is formed in said rail. The rail is adapted to be adjusted forward or backward upon its supporting brackets by 80 means of slots 2' that are formed in the bracket seats, which slots are engaged by retaining bolts 2'', 2'' that extend through the ends of the rails and said slots. Thus when the device is to be utilized for a short 85 animal the retaining bolts 2'', 2'' are loosened and said rail is adjusted rearward, it being obvious that for a larger animal the rail would be moved ahead.

A yoke-bar 4 is anchored to the flooring 90 of the stall by means of a chain 5 as shown, and pivoted to the ends of the yoke-bar are a pair of neck-bows 6, the upper ends of said neck-bows being extended through the rail slot and terminate with alined trunnions 95 6', 6''. The said upper ends of the bows are also each provided with a semi-circular collar 7, 7', the lower face of which collar members are arranged to rest upon the upper face of the rail, whereby the stanchion 100 is held in suspension. When the neck-bows are closed, as shown in Fig. 1, these semi-circular collars serve as means for interlocking said bows, the interlocking being effected by teeth 7'' that extend from one of 105 the collars, which teeth articulate with indentations that are formed in the opposite collar 7', as best shown in Fig. 4.

Secured to the stanchion rail 3 is a bracket having a stud 8 and mounted upon this stud 110 is a lever having oppositely diverging arms 9, 9', the ends of which arms carry wrist-

pins 10, 10'. The trunnion ends 6 and 6' of the neck-bows are journaled in end-hubs 11, 11' of links 12, 12', the opposite ends of said links being respectively pivoted to the wrist-pins 10, 10'. The wrist-pin 10 of the two-arm lever is also provided with an extension on which is swiveled an eared shackle 13, the same being in hinge connection with one end of an individual actuating rod 14, which rod and its connection is upon a different plane from that of the links 12 and 12', the latter being upon the same plane.

The free end of the rod 14 is provided with an apertured head 14' that terminates with a handle extension whereby the rod may be manually operated. The head aperture is adapted to effect coupling engagement with a pin 15 that is carried by a master controlling rod 16 and when it is desired to operate the stanchion independent of the master rod the individual rod is disengaged from the pin 15. When so disengaged, should it be desired to open the neck-bows of the stanchion, the rod is thrust forward to thus oscillate the two-arm lever whereby the neck-bows through their link connections will be spread apart. In this open position the aperture 14' in the head 14 of the individual rod is seated over a locking tongue 17, which locking tongue is secured to the rail section, there being a similar locking tongue 17' provided for the reception of the head aperture when the stanchion is closed. When said stanchion is closed, as shown in Figs. 2 and 3, it will be observed that owing to the fact that the trunnioned ends of its neck-bows are in axial alinement that the stanchion is capable of being oscillated to permit free movement of the neck and head of the animal, it being also observed that when the neck-bows are spread apart or open that the collars 7, 7', serve as supports for said members, the collars being adapted to slide upon the upper face of the overhead rail. It is also apparent that when the stanchion is closed, a straight line drawn between the connecting points of the links 12 and 12' would approximately intersect the fulcrum stud 8 of the two-arm lever, whereby the bow members are automatically and positively locked against thrust movement imparted thereto.

The master rod 16 is slidably mounted in boxes 18 that are formed in the standard portions of the brackets 2, it being understood that said master rod extends through the entire series of alined stanchions, whereby an operator can open or close the series simultaneously, due to the individual rods being in coupling connection with said master rod. When the neck-bows are fully opened, their movement is limited by their upper ends engaging the ends of the slots formed in the rail 3 as best shown in Figs.

1 and 5 and while I have not illustrated any means for locking the master rod in its adjusted positions it is apparent that the standard of that bracket adjacent to the handle of said master rod may be provided with such means accessible to the operator. 70

While I have specifically described the structural features as illustrated in the drawings, for carrying out my invention, it is understood that I may, without departing from the spirit of said invention, substitute other structural features for accomplishing the same results, as are known to those skilled in the art, the principles embodied in the invention being under all conditions unchanged. It is also within the scope of my invention to provide one of the neck-bows with a rigid connection to the yoke-bar, whereby only a single neck-bow is opened or closed through its link connection with the two-arm lever. Furthermore it is apparent that owing to the shackle or universal connections between the lever and individual operating rod, that shift of the sectional rail can be effected, and that said rod may be raised or lowered to effect a coupling connection between the tongues 17, 17', the shackle connections being provided for this purpose. 85 90

I claim:

1. A stanchion comprising a shackled yoke-bar, oppositely disposed bows pivoted thereto, a vertically disposed trunnion carried at the end of each bow upon different horizontal planes, whereby said trunnions are adapted to be axially alined when the bows are closed to form a common pivot point, a slotted rail through which the upper ends of the bows project, a collar carried by each bow at its upper end for engagement with the rail, an oscillatory lever having oppositely extended arms, a link connecting each lever arm and one of the end trunnions of the neck-bows, a master rod, and an individual rod in connection with the oscillatory lever, the opposite end of which lever is detachably secured to the master rod. 95 100 105 110 115

2. A stanchion comprising a shackled yoke-bar, oppositely disposed bows pivoted thereto, a vertically disposed trunnion carried at the end of each bow upon different horizontal planes, whereby said trunnions are adapted to be axially alined when the bows are closed to form a common pivot point, a slotted rail through which the upper ends of the bows project, a collar carried by each bow at its upper end for engagement with the rail, a fulcrumed lever having oppositely extended arms, a wrist-pin carried by each arm, a link in pivotal union with each lever-arm wrist-pin and one of the end shackles of the neck-bows, the lever pivoted ends of the links being arranged to approximately aline with the fulcrum point 120 125 130

of said lever when the bows are closed, whereby the same are locked in said closed position.

3. A stanchion comprising a slotted overhead rail, a fixed support therefor, means for adjusting said rail upon the fixed support, a yoke-bar, means for anchoring the same, bows having their lower ends pivoted to the yoke-bar, their upper ends being extended through the rail slot, vertically disposed trunnions in connection with the upper terminals of the bow rods, the trunnions being upon different horizontal planes, whereby they are adapted to be alined to form a common pivot point when the bows are closed, slideable supporting collars carried by the bow members in engagement

with the upper face of the rail whereby said bows are suspended, an oscillatory two-arm lever, links connecting each arm and one of the bow trunnions, a reciprocal master rod, and an individual operating rod having one end connected to the oscillatory lever and its opposite end in connection with said master rod.

In testimony that I claim the foregoing I have hereunto set my hand at Oconomowoc in the county of Waukesha and State of Wisconsin in the presence of two witnesses.

FREDERICK W. MOLDENHAUER.
